AMMONIUM NITRATE-ALIPHATIC HYDROCARBON-UREA CLATHRATE EXPLOSIVES
 Charles M. Saffer, Jr., Levittown, Pa., assignor to Thiokol Chemical Corporation, Bristol, Pa., a corporation of Delaware
 No Drawing. Filed Nov. 15, 1962, Ser. No. 238,037
 9 Claims. (Cl. 149—45)

This invention relates to blasting explosives and more particularly to explosives in which ammonium nitrate, aliphatic hydrocarbons and urea are the chief constituents.

For some time now, mixtures of ammonium nitrate-aliphatic hydrocarbon explosives have been utilized in commercial applications, such as, in mining and in quarrying. These explosive mixtures are mixed just prior to detonation. The reason for this is that the sensitivity of these explosives greatly decreases upon standing or storage for any extended length of time. This loss of sensitivity is believed to be caused by the separation of the aliphatic hydrocarbon component from the ammonium nitrate apparently because of gravity. The segregation of the aliphatic hydrocarbon component into a distinct phase desensitizes the explosive mixture to such an extent that no substantial explosive force is released upon detonation.

This invention overcomes the above drawbacks of the prior art explosive mixtures by providing ammonium nitrate-aliphatic hydrocarbon explosive mixtures which are stabilized in one instance through the addition of a urea-aliphatic hydrocarbon clathrate to the ammonium nitrate-based explosive and in another instance by "in situ" formation of the clathrate. By these means the separation of the aliphatic hydrocarbon from the ammonium nitrate is prevented such that the explosive mixture retains a constant level of reactivity toward detonation. As a result, the explosive mixture of this invention may be mixed and stored prior to actual use, safely handled and detonated when needed.

Thus it is an object of this invention to prepare an ammonium nitrate-based explosive mixture that can be safely prepared prior to use at the blasting site.

It is another object of this invention to prepare ammonium nitrate-based explosives which retain a constant high level of sensitivity toward detonation for appreciable periods of time. Yet another object of the invention is to prepare a urea-aliphatic hydrocarbon clathrate additive which retards the separation of the hydrocarbon phase from homogeneous ammonium nitrate-aliphatic hydrocarbon containing explosives. Additional objects of this invention will become apparent as this invention is more fully defined.

These objects are accomplished as follows: a solution of urea in an aliphatic alcohol is combined with an aliphatic hydrocarbon under moderate heat and vigorous stirring conditions, until a homogeneous clathrate is obtained. The resultant urea-aliphatic hydrocarbon clathrate is then mixed with the ammonium nitrate component to form the explosive mixture of this invention.

The proportions of the chief constituents of the inventive explosive composition which can be employed to yield a satisfactory composition are as follows: 75-98 parts by weight of ammonium nitrate and 25-2 parts by weight of the urea-aliphatic hydrocarbon clathrate.

Especially good results insofar as inhibiting the loss of sensitivity toward detonation are obtained in explosive compositions consisting of 80 to 94 parts by weight of ammonium nitrate and 20 to 6 parts by weight of the urea-aliphatic hydrocarbon clathrate.

The urea-aliphatic hydrocarbon clathrate in turn comprises 3-6 parts by weight of the urea constituent for each part by weight of the aliphatic hydrocarbon used

2

with 4-5 parts by weight of urea to 1 part by weight of aliphatic hydrocarbon, representing the preferred ratio.

In practicing my invention, the following procedure can be employed: The urea-aliphatic hydrocarbon clathrate is produced by heating together a well-mixed dispersion of a predominantly aliphatic hydrocarbon and a solution of urea in an alkanol at moderately low temperatures with constant mixing until the urea-aliphatic hydrocarbon constituents are homogeneously mixed. The clathrate, a homogeneous, crystalline solid, formed by the urea-aliphatic hydrocarbon mixture is then combined with the ammonium nitrate to yield ultimately a homogenous explosive mixture.

During the formation of the urea-aliphatic hydrocarbon clathrate, the temperature is kept below 65° C. However, it has been found that especially favorable results are obtained in the narrower range of 55° C. to 60° C. The aliphatic hydrocarbon constituents of the clathrate are defined herein as including paraffinic alkanes or aliphatic hydrocarbons as well as the so called aliphatic fatty acids. Thus, these aliphatic hydrocarbons may be chosen from a number of saturated and unsaturated, straight-chain or branched-chain aliphatic hydrocarbons and aliphatic fatty acids. For example, satisfactory results have been obtained using the following: decane, undecane, dodecane, tridecane, tetradecane, pentadecane, hexadecane, heptadecane, octadecane, nonadecane, and eicosane. An especially convenient source of hydrocarbons for this purpose are the so called aliphatic hydrocarbon fractions ordinarily produced during oil refinery operations such as cracking and the like. However, even fuel oil fractions enriched with aliphatic hydrocarbons are satisfactory, as well as fatty acids such as palmitic, stearic, oleic, linoleic and linolenic derived from petroleum refining or other sources. As indicated above, other aliphatic alcohols can be used. Satisfactory results are obtained using such alcohols as ethanol, methanol, isopropanol and propanol among others.

Generally, a homogeneous system is obtained after five minutes of mixing with one minute being the average time. The crystalline, solid urea-aliphatic hydrocarbon clathrate is then combined with the ammonium nitrate at substantially ambient temperature using a mixer with a non-explosive motor in a well-known manner employed in the explosives art. The order of combining the clathrate and ammonium nitrate compounds is not critical.

The invention will be further illustrated by the description in connection with the following specific examples of the practice of it. In these examples and elsewhere proportions are expressed in parts by weight unless otherwise indicated.

EXAMPLE 1

Preparation of the Explosive Compositions of This Invention

To a suitable reaction vessel equipped with heating, cooling and stirring means is added 40 parts by weight of urea dissolved in 160 parts by weight of anhydrous methanol. To 75 g. of this urea-methanol solution is slowly added, at room temperature with stirring, 3.5 g. of an aliphatic hydrocarbon fraction containing primarily C₉-C₂₀ paraffinic hydrocarbons. After the addition is complete, the crystalline urea-aliphatic hydrocarbon clathrate forms and is separated by filtration cooled to room temperature, dried and combined with 94 parts by weight of fine grind ammonium nitrate. A homogeneous mixture is obtained.

EXAMPLE 2

Using the equipment and technique described in Example 1, the procedure of Example 1 is repeated except that 3.5 g. of dodecane is used instead of the paraffinic

fraction. Upon the addition of ammonium nitrate, mixing is continued until a homogeneous mixture is obtained.

EXAMPLE 3

Again the equipment and technique employed in Example 1 are used except that 3.5 g. of 1-decene is used instead of the paraffinic fraction. Mixing is continued after the addition of the ammonium nitrate until a homogeneous mixture is obtained.

EXAMPLE 4

Using the equipment and technique described in Example 1, the procedure of Example 1 is repeated except that 3.5 g. of eicosane is used instead of the paraffinic fraction. Mixing is continued after the addition of the ammonium nitrate until a homogeneous mixture is obtained.

EXAMPLE 5

Preparation of the Inventive Composition by the in Situ Preparation of Urea-Aliphatic Hydrocarbon Clathrate

Using the components described in Example 1, the urea-aliphatic hydrocarbon clathrate is prepared in situ as follows:

94 g. of ammonium nitrate and 3.5 g. of an aliphatic hydrocarbon are combined in an appropriate mixer resulting in a homogeneous mixture. To this mixture is added 75 g. of a urea-methanol solution prepared in accordance with the procedure set forth in Example 1. The mixture is stirred at room temperature for about ten minutes until a urea-hydrocarbon clathrate is formed. The excess urea-methanol solution is filtered off and the remaining solid mixture is dried in air at room temperature. The resultant explosive mixture has identical characteristics to the explosive mixture prepared in Example 1.

EXAMPLE 6

Using the equipment and technique described in Example 5, the procedure is repeated except that the amount of methanol used is greatly decreased. In this example, the 15 g. portion of urea is moistened with methanol. Since there is no liquid phase, no filtration or drying steps are necessary as was the case in Example 5. When the mixing is completed, the resultant explosive mixture is identical to that prepared in Example 5.

EXAMPLE 7

Using the equipment and technique described in Example 5, the following modifications are made shown below.

Ammonium Nitrate, parts by weight	Urea, parts by weight	Aliphatic Hydrocarbon, parts by weight
100	20	6

The resultant explosive mixture is identical to that prepared in Example 5.

EXAMPLE 8

Again the equipment and technique described in Example 5 are used. The modifications are shown below.

Ammonium Nitrate, parts by weight	Urea, parts by weight	Aliphatic Hydrocarbon, parts by weight
100	15	4

The resultant explosive mixture has identical characteristics to that prepared in Example 5.

EXAMPLE 9

Preparation of Further Explosive Compositions

Again the equipment and technique described in the first two examples are used. The modifications shown below are made.

Ammonium Nitrate	Alcohol	Aliphatic Hydrocarbon	Urea
Fine grind	ethanol	dodecane	Same as in Example 1.
Agricultural grade	do	kerosene	Do.
Do	do	oleic acid	Do.

In each instance, homogenous mixtures are obtained.

Stability and Sensitivity Toward Detonation of the Compositions of This Invention Under Prior Art

A. *Separation of the aliphatic hydrocarbon component.*—The explosive mixture of samples of Examples 1 to 9 were examined after 30 days' storage for separation of the aliphatic hydrocarbon components. None of the explosive mixtures exhibited any tendency toward aliphatic hydrocarbon separation. As a control, two samples of ammonium nitrate-aliphatic hydrocarbon mixture prepared according to the prior art method were stored under the same condition and for the same period of time. In both instances, the prior art explosive composition leaked aliphatic hydrocarbon badly indicating extreme segregation.

B. *Constant sensitivity toward detonation.*—The explosive mixtures prepared in Examples 1 to 9 are detonated immediately after preparation, and after prolonged storage, respectively. The testing procedure used was the Picatinny Arsenal impact test and is described in TM 9-1410, pages 43-47, and is the one described herein below. The prior art ammonium nitrate-aliphatic hydrocarbon explosive mixture is used as a control. Detonation is made as before immediately after preparation and after prolonged storage. One pound charges were prepared consisting of the ammonium nitrate urea-aliphatic-hydrocarbon mixture of the invention. A standard electrically fired No. 8 detonator was used to which a five gram tetryl pellet was taped and centered in the explosive mixture. The test results appear below:

Product	Sensitivity	
	After Preparation	After 30 days' storage
Example 1	Explosion	Explosion.
Example 2	do	Do.
Example 3	do	Do.
Example 4	do	Do.
Example 5	do	Do.
Example 6	do	Do.
Example 7	do	Do.
Example 8	do	Do.
Example 9	do	Do.
Prior Art	do	No Explosion.

As can be seen from the above data, the products of the invention are superior to the prior art in both freedom from segregation and in maintaining constant sensitivity toward detonation.

What is claimed is:

1. A blasting explosive comprising a reaction mixture of ammonium nitrate and a urea-aliphatic hydrocarbon clathrate, said aliphatic hydrocarbon clathrate being selected from the group consisting of urea-aliphatic hydrocarbon clathrates and urea-aliphatic fatty acid clathrates in the proportion of 75 to 98 parts by weight of ammonium nitrate and 25 to 2 parts by weight of said urea clathrate, said urea clathrate consisting of 3 to 6 parts by weight of urea to each part of an aliphatic compound selected from the group consisting of aliphatic hydrocarbons and aliphatic fatty acids.

2. The composition of claim 1 in which 94 parts by weight of ammonium nitrate component is combined with 6 parts by weight of urea-aliphatic hydrocarbon clathrate.

3. The composition of claim 1 wherein the aliphatic hydrocarbon constituent of the urea-aliphatic hydrocarbon clathrate is eicosane.

4. The composition of claim 1 wherein the aliphatic fatty acid constituent of the urea-aliphatic fatty acid clathrate is oleic acid.

5. The composition of claim 1 wherein the aliphatic hydrocarbon constituent of the urea-aliphatic hydrocarbon clathrate is dodecane.

6. The composition of claim 1 wherein the aliphatic hydrocarbon constituent of the urea-aliphatic hydrocarbon clathrate is kerosene.

7. The composition of claim 1 wherein the aliphatic hydrocarbon constituent of the urea-aliphatic hydrocarbon clathrate is 1-decene.

8. The process of stabilizing ammonium nitrate-aliphatic hydrocarbon explosive mixtures comprising the step of combining ammonium nitrate with a urea-al-

phatic hydrocarbon clathrate, said aliphatic hydrocarbon clathrate being selected from the group consisting of urea-aliphatic hydrocarbon clathrates and urea-aliphatic fatty acid clathrates, said clathrate being prepared by mixing 3 to 6 parts by weight of urea with each part of aliphatic hydrocarbon, so that the resulting ammonium nitrate-urea-aliphatic hydrocarbon clathrate comprises 75 to 98 parts by weight of ammonium nitrate and 25 to 2 parts by weight of urea-aliphatic hydrocarbon clathrate.

9. The process of stabilizing ammonium nitrate-aliphatic hydrocarbon explosive mixtures, said explosive mixtures containing 2 to 6 parts by weight of aliphatic hydrocarbon to each 100 parts by weight of ammonium nitrate which comprises the step of intimately mixing said explosive compositions with 10 to 20 parts by weight of urea.
